DESIGN FOR A GAS BURNER

Clarence E. Clifton, Tulsa, Okla.

Application January 23, 1936, Serial No. 60,756

Term of patent 14 years

To all whom it may concern:

Be it known that I, Clarence E. Clifton, a citizen of the United States, residing at Tulsa, in the county of Tulsa and State of Oklahoma, have invented a new, original, and ornamental Design for a Gas Burner, of which the following is a specification, reference being had to the accompanying drawing, forming part thereof.

In the drawing:

Fig. 1 is a top plan view of a gas burner, showing my new design.

Fig. 2 is a side elevation of the same.

Fig. 3 is an end elevation.

Fig. 4 is a bottom plan view.

I claim:

The ornamental design for a gas burner, as shown.

CLARENCE E. CLIFTON.
